A. J. Ford Inventor

By his attorney Scant. Fins.

UNITED STATES PATENT OFFICE.

ALBERT J. FORD, OF NEW YORK, N. Y., ASSIGNOR TO FUCHS & LANG MANUFACTURING COMPANY, OF NEW YORK, N. Y., A CORPORATION OF NEW YORK.

COATING-MACHINE.

No. 802,745.

Specification of Letters Patent.

Patented Oct. 24, 1905.

Application filed June 6, 1904. Renewed September 11, 1905. Serial No. 278,036.

To all whom it may concern:

Be it known that I, ALBERT J. FORD, a citizen of the United States, residing at the city of New York, borough of Brooklyn, county of 5 Kings, and State of New York, have invented certain new and useful Improvements in Coating-Machines, of which the following is a specification.

The object of my invention is to provide a new and improved coating-machine for coating or covering metal sheets with varnish, or ground colors in oil or other suitable substance, or printing-ink, which machine is simple in construction and can readily be adjusted not 10 to feed any ink, color, or varnish when metal sheets are not being fed through the same, thus preventing the supporting-roller of the machine from being covered with ink, color, or varnish, and thereby also preventing 15 coloring or disfiguring of the under sides of the metal plates by said supporting-roller and a waste of ink, color, or varnish.

In the accompanying drawings, in which like letters of reference indicate like parts in 20 all the figures, Figure 1 is a side view of my improved coating-machine, parts being broken away. Fig. 2 is a front view of the same, parts being broken away. Fig. 3 is a detail view.

30 The machine is built upon and supported by a frame composed of two side supports A, united by rods A'. An iron supporting-roller B for the sheets to be coated is journaled in boxes B', mounted to be adjusted or shifted 35 vertically in guide-slots A² of the supports A, and each box B' is pivotally connected at its bottom with a connecting-rod C, the lower end of which is pivotally connected with a crank-arm D, which crank-arm projects from the 40 rock-shaft D', mounted in the supports A.

To one end of the rock-shaft D' a handle-arm E is secured, which is provided with a segmental slot E', concentric with the shaft D', and into said slot a pin E² projects from the 45 outer side of one of the supports A for the purpose of limiting the movements of the handle-arm, and consequently of the rock-shaft D'.

The connecting-rods C are made adjustable 50 and preferably consist each of two end sections C', screwed into a middle section C².

From each journal-box B' a bracket F' projects, and in these brackets a rock-shaft F is

mounted parallel with the roller B, and from said shaft a scraper-plate F² extends to the 55 periphery of the roller B, the scraper being secured to the under side of the shaft. The scraper-plate F² is so disposed in relation to the roller B as to be inclined toward said roller in a direction which is the opposite of 60 the direction of rotation—that is to say, the roller moves toward the edge of the inclined scraper in the direction from the free end of the scraper toward the fixed end of the same.

From the top of the rock-shaft F two arms 65 F³ extend in the direction from the roller B and at their free ends can contact with adjustable stops F⁴, secured in a suitable cross-piece F⁵, uniting two brackets A³, projecting from the supports A and supporting a feed-table G. 70

A composition roller H is mounted in vertically-adjustable bearings H', guided in the supports A, and presses upward by springs H² and downward by adjusting-screws H³, the roller H being mounted above the roller B 75 and adapted to be in contact with the latter.

An inking-roller box J contains inking-rollers J' J² in contact with each other, the roller J² being in contact with the roller H. An inking fountain or pan a is located in the bottom of the box or frame, in which fountain the inking-roller J' is immersed, and by contact inks the roller J², which in turn transmits the ink to the roller H. At each end of the two rollers J' and J² a scraper b is located, 80 which is in contact with the ends of the three rollers and is inclined from the top of the roller H toward the roller J', so as to extend across the ends of said rollers H, J', and J² at or directly below the points of contacts of 85 the rollers H and J² and J² and J'. The surplus color is pressed between the two contact circumferential surfaces of the rollers toward the ends and passes into the scraper b, down which it flows and drops back into the fountain, and thus prevents color dropping upon the other parts of the machine. The said scrapers b are suspended by arms d from a transverse overhead shaft e, to which they are attached, which shaft is adapted to rock 90 in bearings f and can be locked in place by means of a screw g after proper adjustment of the scrapers.

The driving-shaft K carries the belt-pulleys K' K² and the pinion L at one end and the cog- 105 wheel M at the opposite end. The pinion L

engages the cog-wheel N, secured on one end of the roller H outside of the journal-box. The cog-wheel N engages a pinion O on a stud O', projecting from one support A, and the pinion O' engages a cog-wheel P on one end of the shaft of the upper roller H, which cog-wheel P engages a cog-wheel Q² on the upper inking-roller J², and this cog-wheel engages a cog-wheel Q' on the inking-roller J'. Delivery-tapes R pass over a roller T, mounted between the supports A.

A drip-pan V is located beneath the roller B.

The operation is as follows: The metal sheets or plates to be coated are fed from the feed-table G between the rollers B and H, the face to be coated being uppermost. The ink or color transferred from the fountain to the composition roller H is transferred from the latter upon the upper surface of the metal sheet or plate, and the coated plate or sheet passes upon the delivery-tapes R and is carried off by the same. During the operation described the lower or supporting roller B is in raised position, and any ink or color that adheres to the same is scraped off by the scraper F² and drips into the drip-pan V. When the machine is running idle—that is, when no sheets are being fed—the supporting-roller B must be lowered and brought out of contact with the upper or composition roller H, as otherwise ink or color would be constantly transferred upon the supporting-roller B from the composition roller H. To lower the supporting-roller, the handle-arm E is swung upward, whereby the crank-arms D are swung downward and pull downward the connecting-rods C and the roller B. During such downward movement of the roller B the cog-wheel N rolls on the pinion L without being disengaged from the latter. At the same time the scraper-shaft F is moved downward and the scraper F² is permitted to drop out of contact with the periphery of the roller B. To raise the roller B, the handle-arm E is swung downward, and at the same time the scraper-shaft F is raised, and as thereby the outer or free ends of the arms F³ are pressed against the stops F⁴ the edge of the scraper is pressed against the periphery of the roller B. The scraper is thus automatically engaged with and disengaged from the roller and the driving-gear, for the roller is not disengaged by raising or lowering said roller.

As the lower roller can be lowered, the entire machine can be thoroughly cleaned without detaching or removing any of the rollers from the machine.

Having described my invention, what I claim as new, and desire to secure by Letters Patent, is—

1. In a machine for coating metal sheets with varnish or oil or similar colors, the combination with a composition roller and means for supplying the same with color, of a supporting-roller beneath the composition roller

and movable toward and from the latter, a scraper mounted to move vertically with said vertically-movable roller and means for automatically engaging the scraper with the vertically-movable roller when the latter is raised and automatically disengaging the scraper from the roller when the roller is lowered, substantially as set forth. 70

2. In a machine for coating metal sheets with varnish or oil or similar colors, the combination with a composition roller and means for supplying the same with ink, of a supporting-roller beneath the composition roller and a rock-shaft mounted to move up and down with the vertically-adjustable roller, a scraper on said rock-shaft extending to said supporting-roller, arms on said shaft extending in the direction from said supporting-roller and stops with which said arms can contact, substantially as set forth. 75

3. In a machine for coating metal sheets with varnish, oil or similar colors, the combination with a composition roller and means for supplying the same with ink, of a supporting-roller beneath the composition roller, a rock-shaft for shifting said supporting-roller, cranks on the same, connecting-rods connecting said cranks with the journal-boxes of the supporting-roller, a handle-arm on said rock-shaft, a cog-wheel on the vertically-adjustable supporting-roller, and a pinion engaging said cog-wheel and on which pinion said cog-wheel is adapted to roll during the up and down movements of said roller, substantially as set forth. 85

4. In a machine for coating metal sheets with varnish or oil or similar colors, the combination with a composition roller, of a supporting-roller beneath the composition roller, a fountain, an inking-roller within the fountain, a second inking-roller in contact with the inking-roller in the fountain and with the composition roller and a scraper extending across the ends of the two inking-rollers and the composition roller, at the points of contact of said several rollers, substantially as set forth. 100

5. In a machine for coating metal sheets with varnish or oil or similar colors, the combination with a composition roller, of a supporting-roller beneath the composition roller, a fountain, an inking-roller within the fountain, a second inking-roller in contact with the inking-roller in the fountain and with the composition roller, a scraper extending across the ends of the two inking-rollers and the composition roller, at the points of contact of the several rollers, and means for adjusting said scraper, substantially as set forth. 115

6. In a machine for coating metal sheets with varnish or oil or similar colors, the combination with a composition roller, of a supporting-roller beneath the composition roller, a fountain, an inking-roller within the fountain, a second inking-roller in contact with the

the inking-roller in the fountain and with the composition roller, a scraper extending across the ends of the two inking-rollers and the composition roller at the points of contact of the several rollers, a shaft above the scraper, arms extending from said shaft to the scraper and connected with said shaft and scraper, and means for locking the shaft in place after adjustment of the scraper, substantially as set forth.

7. In a machine for coating metal sheets with varnish, oil or similar colors, the combination with a supporting-roller, of a scraper-plate having one edge in contact with the pe-

riphery of the said roller and mounted on a suitable support and so disposed in relation to the roller that the roller in rotating moves toward the edge of the scraper in the direction from the free end of the scraper toward the fixed end of the same, substantially as set forth.

In testimony whereof I have signed my name to this specification in the presence of two subscribing witnesses.
